Pedersen, P.A.(57) **ABSTRACT**

An electronic cigarette has a vaporizer to produce vapor to be delivered to its mouth end. The vaporizer includes a tube having inlet and outlet ends. A porous matrix containing a vaporizable liquid, extends around the tube. Wicking fibers extend through side openings in the tube and are configured to wick the vaporizable liquid from the porous matrix into the tube, and electrical heater coil is powered by a battery to vaporize liquid on the wicking fibers in the tube, so that vapor is supplied along the tube end when the user draws on mouth end. The wicking diverge from the openings into fan shaped spread regions around outer surface of the tube so as to contact and receive the vaporizable liquid by capillary action from the matrix.

ELECTRONIC CIGARETTE
RELATED APPLICATIONS

The present application is a National Phase entry of PCT Application No. PCT/GB2014/051334, filed Apr. 30, 2014, which claims the benefit of GB Application No. 1307962.9, filed May 2, 2013, each of which is incorporated herein by reference in its entirety.

TECHNICAL FIELD

Embodiments relate to an electronic cigarette.

SUMMARY

Embodiments of electronic cigarette described herein comprise an electronic cigarette comprising a generally cylindrical housing with a proximal mouth end and a distal end, and within the housing: a vaporizer to produce vapor to be delivered to the mouth end, a battery, and sensor circuitry to detect a user drawing on the mouth end and connect the battery to power the vaporizer to produce vapor, the vaporizer comprising: a tube having inlet and outlet ends and extending longitudinally of the housing, supports at opposite ends of the tube for directing airflow into and out of the tube from the inlet to the outlet, a porous matrix containing a vaporizable liquid extending around the tube, wicking fibers extending through side openings in the tube and configured to wick the vaporizable liquid from the porous matrix into the tube, and an electrical heater coil in the tube configured to be powered by the battery to vaporize liquid on the wicking fibers in the tube, so that vapor is supplied along the tube to the outlet end when the user draws thereon, wherein the wicking fibers diverge from one another from the side openings and are spread over the outer surface of the tube so as to contact and receive the vaporizable liquid by capillary action from the matrix.

The spread fibers may lie spread over the outer surface of the tube in an arc which at its outermost spread subtends an angle at the central longitudinal axis of the tube of at least 30°, for example in the range 40°-150°.

The spread wicking fibers may extend towards the inlet end or the outlet end of the tube or both.

The supports for the tube may include a mouth end stopper that is push-fitted into the mouth end of the housing, which includes a mouthpiece spigot onto which the outlet end of the tube is received, and an outlet passageway extending through the spigot to provide an outlet for vapor from the tube.

Also, the supports for the tube may include an annular support member that includes a peripheral surface to engage with the interior of the housing, an inlet spigot on which the inlet end of the tube is mounted, and an inlet passageway extending through the inlet spigot to provide an inlet for air into the tube.

BRIEF DESCRIPTION OF THE DRAWINGS

Embodiments of electronic cigarette will now be described in more detail by way of example with reference to the accompanying drawings, in which:

FIG. 1 is a schematic perspective view of an electronic cigarette.

FIG. 2 is a longitudinal section through the electronic cigarette shown in FIG. 1.

2

FIG. 3 is an exploded, partial perspective view of the vaporizer illustrated in FIG. 2, showing its heater element in a tube.

FIG. 4 is an enlarged portion of the sectional view shown in FIG. 2 in the region of its heater element.

FIGS. 5A, 5B and 5C illustrate alternative spread arrangements for the wicking fibers on the tube's outer surface.

FIG. 6 is a cross sectional view of the tube and the heater element along the line B-B' of FIG. 5B, showing the angle subtended by the spread fibers at the central longitudinal axis of the tube.

FIG. 7 is a schematic view of portions of an alternative embodiment of vaporizer.

15

DETAILED DESCRIPTION

Referring to FIGS. 1 and 2, an electronic cigarette 1 includes a generally cylindrical housing 2 conveniently in the form of a tube of plastics material that extends from a proximal or mouth end 3 to distal end 4. An end cap 5 of translucent plastics material is push-fitted into the distal end 4 and a mouth end stopper 6 is similarly fitted into the mouth end 3. The tube 2 is flexible and given rigidity in part by its internal components, as will be described in more detail hereinafter. The tube in one example is made of polypropylene.

As shown in FIG. 2, the end cap 5 includes an air inlet 7 so that when the user draws on the mouth end 3, air is drawn into the housing 2 and vapor is supplied to the user through the mouth end 3 as will be described hereinafter.

The housing 2 contains a battery 8, sensor circuitry 9 and a vaporizer 10 that produces a vapor to be supplied to the user.

The vaporizer 10 is illustrated in more detail in FIGS. 3 and 4. The vaporizer 10 includes a tube 11, conveniently made of fiberglass material which extends from an inlet end 12 to outlet end 13. The tube 11 includes diametrically opposed side openings 14a,b. Wicking fibers 15 extend through the side openings 14a,b across the interior of the tube. An electrical heater coil 16 extends diametrically across the tube 11, with the wicking fibers 15 passing axially within the coil 16. Electrical leads 17a, 17b supply electrical power to the coil 16 from the battery 8 under the control of the sensor circuitry 9 shown in FIG. 2.

The wicking fibers 15 conveniently comprises a bundle of fibers made of heat resistant material such as fiberglass, which are constrained in a generally cylindrical configuration where they extend diametrically across the tube 11 by the coil 16 and the side openings 14a, 14b. However, as shown schematically in FIG. 5A, the fibers 15 diverge from one another from the side openings 14a, 14b into generally fan shaped, spread regions 15a, 15b which lie on the curved outer surface 11a of the tube 11. In the example shown in FIGS. 2 and 3, the fan shaped, spread regions 15a, 15b both extend from the side openings 14a, 14b towards the outlet end 13 of tube 11.

Alternative spread wicking fiber configurations are shown in FIGS. 5B and 5C.

In FIG. 5B, the fibers 15 emanating from side opening 14a are split into two bundles 15a' and 15a" which diverge from the opening 14a in opposite directions along the outer surface 11a of the tube 11. The fibers 15b emanating from opening 14b can be similarly split into two bundles 15b' and 15b" which diverge from the opening 14b in opposite directions along the outer surface 11a of the tube 11.

In FIG. 5C, the fibers 15a emanating from side opening 14a diverge from the side opening along the outer surface

11a of the tube 11 towards its outlet end 13. The fibers 15b emanating from opening 14b diverge from the opening 14b along the outer surface 11a of the tube 11 toward the inlet end 12.

It will be appreciated that various permutations of the various wicking fiber spreading arrangements shown in FIGS. 5A, 5B and 5C can be used for the different fiber groupings. In the illustrations of FIGS. 5A, 5B and 5C the spread wicking fibers are all configured so as to be spread symmetrically of the central longitudinal axis of symmetry A-A' of the tube 11 but it will be appreciated that asymmetrical wicking fiber configurations can also be used.

The spread configuration of the wicking fibers 15 over the outer surface 11a of the tube improves the operation of the vaporizer 10, as will be explained in more detail hereinafter.

A porous matrix that comprises first and second sheets of fibrous material 18, 19 is loaded with a vaporizable material, for example a nicotine and glycerol solution. The sheet 18 has a lower surface area and absorbency than the surrounding sheet 19 which can retain a larger volume of the liquid. Typically, the sheet 19 has a larger pore size than the sheet 18. The sheet 18 however facilitates transfer of the liquid to the wicking fibers 15 so that the liquid is wicked along the core of the heater coil 16.

One end of the vaporizer 10 includes an annular support member 20 that has a peripheral surface 21 that engages with the interior surface of the cylindrical housing 2. The annular support member 20 has a generally circular end face 22 extending diametrically across the housing 2 from which an axial inlet spigot 23 extends towards the mouth end 3 and receives the inlet end 12 of tube 11. The overlying ends of the sheets 18, 19 are retained between an annular, depending flange 24 and the inlet spigot 23 at the inlet end of tube 11, and generally fill the space between the interior surface of housing 2 and the tube 11. The annular support member 20 is conveniently flexible and made of silicon for example, so that it can be easily manipulated into housing 2 during manufacture. The sheets 18, 19 are wrapped around the tube 11 and thereby locate the wicking fibers 15 along the length of the outer surface of the tube 11. Spigot 23 includes a through hole to provide an air inlet passageway 23a into the tube 11.

The mouth end stopper 6 includes a mouthpiece spigot 25 that receives the outlet end 13 of tube 11. The end stopper 6 includes an axial outlet passageway 26 through the spigot to pass vapor to a user through the mouth end 3 of housing 2. Also, the mouth end stopper 6 includes a depending flange 27 so that the stopper 6 can be push-fitted into the mouth end 3 of housing 2. The outlet end 13 of tube 11 may extend slightly beyond the matrix 18, 19.

Thus there is a gap between the matrix and the mouth end 3 of the housing 2. Also, the mouthpiece spigot 25 which extends into the tube outlet end 13 is longer than the depending flange 27 that engages with the housing 2, so as to provide a gap between the porous matrix 18, 19 and the end stopper 6. This arrangement prevents or reduces leakage of the liquid held in the sheets 18, 19 through the mouth end 3 of the housing.

Thus, the annular support member 20 and the mouth end stopper 6 with their respective spigots 23, 25 cooperate with the tube 11 and the housing 2 to provide a closed plenum containing the porous sheets 18, 19 so as to retain the nicotine containing liquid in the sheets 18, 19 without leakage from the housing 2, and to allow the liquid to wick along wicking fibers 15 to be vaporized on operation of the heater coil 16.

An advantage of the spread configuration of fibers 15a, 15b around the outer surface 11a of tube 11 is that the area of contact between the sheet 18 of the porous matrix is maximized and extends around the circumference of the outer surface 11a of the tube 11, which improves the wicking effect performed by the fibers 15 and ensures that the liquid in the porous matrix 18, 19 is drained from around a major part of the circumferential extent of the tube 11, which assists in drawing substantially all of the liquid from the matrix by the wicking action for vaporization.

Referring to FIG. 6, which shows a transverse section through the tube 11, the fibers 15 are shown threaded through the coil 16 and diverging into the generally fan shaped spread regions 15a, 15b around the outer surface 11a of the tube 11. The outermost or largest circumferential spread of the fan shaped spread wicking fiber region 15a subtends an angle θ with the central longitudinal axis A-A' of the tube 11 and improved wicking occurs when the maximum value of θ is at least 30°, i.e., the angle θ subtended by the widest part of the fan shaped region 15a $0 \geq 30^\circ$, such as 40° $\leq 0 \leq 150^\circ$. The fiber region 15b is similarly spread in FIG. 6 but a different value of θ could be used falling within the aforesaid range. Also the angle θ can be considered as the azimuth in polar coordinates from the axis A-A' such that the azimuth corresponding to the widest part of the fan shaped region falls within the aforesaid range.

A washer 28, conveniently made of rigid plastics material such as polypropylene, is provided between the vaporizer 10 and battery 8 to provide rigidity to the housing 2 in the region of the annular support member 20. The washer 28 includes an air passageway opening 29 and also openings 30 which receive the electrical leads 17a, 17b. The tubular housing 2 thus is relatively rigid to the touch of the user's fingers in the region of the battery 8 and the washer 28 but is more resilient to the touch in the region containing the vaporizer 10 to provide characteristics of tactility that are similar to those of a conventional tobacco containing cigarette.

An air passageway extends from the inlet opening 7 in the end cap 5 between the sensor circuitry 9 and battery 8 to the air passageway 29 in the washer 28 and thence to the inlet 12 of tube 11.

The sensor circuitry 9 may include a light source in the form of LED 31 which, when operated is visible through the translucent end cap 5.

When the user draws on the mouth end 3, air is drawn through the air inlet 7 in the direction of arrow A past the battery 8 and into the tube 11. The drawing action reduces the air pressure within the housing 2, which is sensed by the sensor circuitry 9. In response, electrical power from the battery 8 is switched by the sensor circuitry 9 to pass through leads 17a, 17b and energize heater coil 16. As a result, liquid which has been wicked by the wicking fibers 15 from the surrounding porous matrix layers 18, 19 is heated and thereby vaporized so that a stream of nicotine containing vapor is passed through the outlet passageway 26 for the user. Also, in response to the pressure reduction, the sensor circuitry illuminates the LED 31 to mimic the burning of a conventional tobacco containing cigarette.

Also, referring to FIGS. 3 and 4, atomization apertures 32 are formed in the tube 11 so that when the user draws on the mouth end 3, the resulting pressure reduction in tube 11 draws liquid from the surrounding porous matrix layers 18, 19 through the apertures 32 and as a result, the liquid is atomized, thereby producing an atomized stream 33 shown in FIG. 4. In this example, the atomization apertures 32 are provided between the inlet end 12 of tube 11 and the heater

coil 16 so that the atomized droplets 33 then pass the heater 16, which encourages further vaporization of the atomized liquid.

Typically, the atomization apertures 32 are of a diameter between 0.1-0.5 mm. In the example of FIG. 3, the atomization apertures 32 are shown diametrically opposite one another but other configurations are possible, for example a distributed arrangement along the tube 11, which may be spatially uniform or otherwise. Also, one or more of apertures 32 may be provided downstream of the heater coil 16, 10 towards the outlet end of the tube 11.

A modified arrangement is illustrated in FIG. 7 with an alternative form of side openings to receive the wicking fibers 15. The coil 16 can be slid into an elongate slot 34 formed in tube 11 which is then closed by means of an overlying cylindrical sheath 35 that is conveniently made of fiberglass material and slid into place from the outlet end 13 of tube 11. In this example, the spread wicking fibers 15 extend towards the inlet opening 12 of tube 11 rather than the outlet end 13, with the advantage that their ends can be sandwiched between the tube 11 and the porous matrix sheet, and held firmly between the region of the tube 11 on spigot 23 and the depending flange 24 of the annular support member 20.

In another modification, the device shown in FIGS. 1 and 2 may have a two part housing 2 so that the vaporizer 10 is attached to the battery 8 and sensor circuitry 9 by a releasable coupling (not shown) along hatched line X shown in FIG. 2.

In order to address various issues and advance the art, the entirety of this disclosure shows by way of illustration various embodiments in which that which is claimed may be practiced and provide for a superior electronic cigarette. The advantages and features of the disclosure are of a representative sample of embodiments only, and are not exhaustive and/or exclusive. They are presented only to assist in understanding and teach the claimed features. It is to be understood that advantages, embodiments, examples, functions, features, structures, and/or other aspects of the disclosure are not to be considered limitations on the disclosure as defined by the claims or limitations on equivalents to the claims, and that other embodiments may be utilized and modifications may be made without departing from the scope and/or spirit of the disclosure. Various embodiments may suitably comprise, consist of, or consist essentially of, various combinations of the disclosed elements, components, features, parts, steps, means, etc. In addition, the disclosure includes other inventions not presently claimed, but which may be claimed in future.

The invention claimed is:

1. An electronic cigarette comprising a generally cylindrical housing with a proximal mouth end and a distal end, and within the housing:
  - a vaporizer to produce vapor to be delivered to the mouth end;
  - a battery; and
  - sensor circuitry to detect a user drawing on the mouth end and connect the battery to power the vaporizer to produce vapor;
 the vaporizer comprising:
  - a tube having inlet and outlet ends and extending longitudinally of the housing,
  - supports at opposite ends of the tube for directing airflow into and out of the tube from the inlet to the outlet,
  - a vaporizable liquid holder containing a vaporizable liquid extending around the tube,

wicking fibers extending through side openings in the tube and configured to wick the vaporizable liquid from the vaporizable liquid holder into the tube, and an electrical heater coil in the tube configured to be powered by the battery to vaporize liquid on the wicking fibers in the tube, so that vapor is supplied along the tube to the outlet end when the user draws thereon,

wherein the wicking fibers diverge from one another from the side openings and are spread over the outer surface of the tube so as to contact and receive the vaporizable liquid by capillary action from the matrix.

2. An electronic cigarette according to claim 1 wherein the spread wicking fibers lie spread over the outer surface of the tube in an arc which at its outermost spread subtends an angle (θ) at the central longitudinal axis of the tube of at least 30°.

3. An electronic cigarette according to claim 1 wherein the spread wicking fibers lie spread over the outer surface of the tube in an arc which at its outermost spread subtends an angle (θ) at the central longitudinal axis of the tube having a value in the range 40°-150°.

4. An electronic cigarette according to claim 1 wherein the spread wicking fibers extend towards the inlet end of the tube.

5. An electronic cigarette according to claim 1 wherein the spread wicking fibers extend towards the outlet end of the tube.

6. An electronic cigarette according to claim 1 wherein the wicking fibers emanating from at least one of the side openings are configured in first and second bundles which are spread in different directions along the tube.

7. An electronic cigarette according to claim 1 wherein the supports include a mouth end stopper that is push-fitted into the mouth end of the housing, the mouth end stopper including a mouthpiece spigot onto which the outlet end of the tube is received, and an outlet passageway extending through the spigot to provide an outlet for vapor from the tube.

8. An electronic cigarette according to claim 7 including a gap between the vaporizable liquid holder and the mouth end stopper.

9. An electronic cigarette according to claim 1 wherein the supports include an annular support member including a peripheral surface to engage with an interior of the housing, an inlet spigot on which the outlet end of the tube is mounted, and an inlet passageway extending through the inlet spigot to provide an inlet for air into the tube.

10. An electronic cigarette according to claim 8 wherein the annular support member includes a depending peripheral flange such that the vaporizable liquid holder is retained between the mouth end stopper and the flange.

11. An electronic cigarette according to claim 10 wherein ends of the wicking fibers are retained sandwiched between the tube and the vaporizable liquid holder between the spigot and the flange.

12. An electronic cigarette according to claim 9 including a washer between the annular support member and the battery.

13. An electronic cigarette according to claim 1 including an air inlet opening at the distal end of the housing.

14. An electronic cigarette according to claim 13 including an air feed passageway between the battery and the housing, extending from the air inlet opening to the inlet end of the tube.

15. An electronic cigarette according to claim **1** wherein the sensor circuitry is disposed between the battery and the distal end of the housing.

16. An electronic cigarette according to claim **1** including a light source powered by the battery under the control of the sensor circuitry to be illuminated in response to the user drawing on the mouth end. 5

17. An electronic cigarette according to claim **16** wherein the light source is disposed at the distal end of the housing.

18. An electronic cigarette according to claim **1** including 10 an end cap push-fitted into the distal end of the housing.

19. An electronic cigarette according to claim **1** wherein the housing comprises a first part containing the battery releaseably coupled to a second part containing the vaporizer. 15

20. An electronic cigarette according to claim **1** wherein the vaporizable liquid holder comprises inner and outer sheets of overlying fibrous material with the outer sheet having a greater pore size than the inner sheet for wicking the liquid to the inner sheet by capillary action. 20

21. An electronic cigarette according to claim **1** including an atomization aperture in the tube configured to allow liquid to be drawn into the tube from the vaporizable liquid holder so as to be atomized by passage through the aperture when the user draws on the mouth end. 25
